[57] **CLAIM**

The ornamental design for a storage container for a miniature disk cartridge, as shown and described.

DESCRIPTION

FIG. 1 is a top, front left side perspective view of the present invention in the open position;

FIG. 2 is a front elevational view of a storage container for a miniature disk cartridge of FIG. 1;

FIG. 3 is a rear elevational view of a storage container for a miniature disk cartridge of FIG. 1;

FIG. 4 is a top plan view of a storage container for a miniature disk cartridge of FIG. 1 with the bottom plan view being a mirror image thereof;

FIG. 5 is a left side elevational view of a storage container for a miniature disk cartridge of FIG. 1 with the right side elevational view being a mirror image thereof;

FIG. 6 is a cross-sectional view along line 6—6 of FIG. 7;

FIG. 7 is a top, front, left side perspective view of the storage container for a miniature disk cartridge of the present invention in the open position, the broken lines showing graphic material in FIGS. 7 through 10, and FIGS. 12, 13, 15 and 16 for illustrative purposes only, forming no part of the claimed design;

FIG. 8 is a front elevational view of a storage container for a miniature disk cartridge of FIG. 7;

FIG. 9 is a rear elevational view of a storage container for a miniature disk cartridge of FIG. 7;

FIG. 10 is a top plan view of a storage container for a miniature disk cartridge of FIG. 7 with the bottom plan view being a mirror image thereof;

FIG. 11 is a left side elevational view of a storage container for a miniature disk cartridge of FIG. 7 with the right side elevational view being a mirror image thereof;

FIG. 12 is a cross-sectional view along line 12—12 of FIG. 8;

FIG. 13 is a top front left side perspective view of the present invention in the closed position;

FIG. 14 is a front elevational view of a storage container for a miniature disk cartridge of FIG. 13;

FIG. 15 is a rear elevational view of a storage container for a miniature disk cartridge of FIG. 13;

FIG. 16 is a top plan view of a storage container for a miniature disk cartridge of FIG. 13 with the bottom plan view being a mirror image thereof;

FIG. 17 is a left side elevational view of the storage container for a miniature disk cartridge of FIG. 13 with the right side elevational view being a mirror image thereof; and,

FIG. 18 is a cross-sectional view along line 18—18 of FIG. 14.
